US00D800555S

(12) **United States Design Patent** (10) **Patent No.:** **US D800,555 S**
(45) **Date of Patent:** **** Oct. 24, 2017**

(54) **SPRAYER**

(71) Applicant: **Coach, Inc.**, New York, NY (US)
(72) Inventor: **Fabien Baron**, New York, NY (US)
(73) Assignee: **Coach, Inc.**, New York, NY (US)
(**) Term: **15 Years**
(21) Appl. No.: **29/542,891**

(22) Filed: **Oct. 19, 2015**

(51) **LOC (10) Cl.** **09-07**

(52) **U.S. Cl.**

USPC **D9/448; D9/689**

Primary Examiner — Thomas Johannes

Assistant Examiner — Catherine Posthauer

(57) **CLAIM**

The ornamental design for a sprayer, as shown and described.

DESCRIPTION

FIG. 1 is a perspective view of a sprayer, showing my new design;

FIG. 2 is a top plan view thereof;

FIG. 3 is a bottom plan view thereof;

FIG. 4 is a right side view thereof;

FIG. 5 is a left side view thereof;

FIG. 6 is a front view thereof; and,

FIG. 7 is a rear view thereof.

The dashed lines in the drawing views depict portions of the design that form no part of the claim.

1 Claim, 7 Drawing Sheets
